(57) **CLAIM**

The ornamental design for a door for orthodontic bracket, as shown and described.

DESCRIPTION

FIG. 1 is a top, front, left perspective view of the door for orthodontic bracket, the top, front, right perspective view being a mirror image thereof;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The evenly spaced broken lines and adjacent unshaded surfaces show portions of the door for orthodontic bracket that form no part of the claimed design. The dash-dot-dash broken lines define the boundaries of the claim and form no part of the claimed design.
